[57] CLAIM

The ornamental design for a silverware basket, as shown and described.

DESCRIPTION

FIG. 1 is a perspective view of the silverware basket showing our new design, one lid shown in an open position; FIG. 2 is an enlarged right end view thereof, with the lid shown in a closed position;

FIG. 3 is a front elevational view of the silverware basket of FIG. 2, the left end view being a mirror image thereof; FIG. 4 is a rear elevational view of the silverware basket of FIG. 2;

FIG. 5 is a top plan view of the silverware basket of FIG. 2; and,

FIG. 6 is a bottom plan view of the silverware basket of FIG. 2.
